(57) **CLAIM**

The ornamental design for a glass head fishing lure, as shown and described.

DESCRIPTION

FIG. 1 is a perspective top view of one embodiment of a glass head fishing lure;

FIG. 2 is a perspective bottom view thereof;

FIG. 3 is a top view thereof;

FIG. 4 is a left side view thereof, the right side view being a mirror image of the left side;

FIG. 5 is a bottom view thereof;

FIG. 6 is a front view thereof;

FIG. 7 is a rear view thereof;

FIG. 8 is a perspective top view of a glass head fishing lure with an attached skirt;

FIG. 9 is a perspective bottom view of the lure illustrated in FIG. 8;

FIG. 10 is a perspective bottom view of a glass head fishing lure with a grub having multiple swirl tails;

FIG. 11 is a perspective top view of the lure illustrated in FIG. 10;

FIG. 12 is a perspective top view of a glass head fishing lure with a grub having a fuzzy tail; and,

FIG. 13 is a top view of a glass head fishing lure with a treble hook and propeller.

The broken lines are for illustrative purposes only and form no part of the claimed design.
